RESONANT LINE OSCILLATOR

James L. Clark, Chicago, Ill., assignor to the
United States of America as represented by
the Secretary of War

Application January 29, 1946, Serial No. 644,169

6 Claims. (Cl. 250—36)

1

This invention relates generally to electrical apparatus and in particular to resonant line oscillators.

In the prior art, oscillators or generators often used in the ultra-high frequency range comprise a pair of thermionic tubes connected in a push-pull tuned-plate tuned-grid circuit, in which a first resonant transmission line is coupled between the anode electrodes and a second resonant transmission line is coupled between the grid or control electrodes. The lines may include short-circuiting members for tuning purposes. The frequency range of such a generator may be extended by placing an inductance in parallel with each resonant circuit, permitting the generation of higher frequencies. Such inductances may each be of strap form for use in ultra-high frequency oscillators, and may be termed backlines.

It is an object of this invention to provide simple means for increasing the operating frequency range of a resonant line oscillator.

It is a further object of the invention to provide a simple structure which permits ready connection or removal of an inductance between terminal pins of thermionic tubes.

Other objects, novel features and advantages of this invention will suggest themselves to those skilled in the art and will become apparent from the following description of the invention taken in connection with the accompanying drawing in which:

Fig. 1 is a front view showing a structure embodying the principles of this invention;

Fig. 2 is a side view of Fig. 1; and

Fig. 3 illustrates the equivalent electrical circuit of which the structure shown in Figs. 1 and 2 forms a part.

Referring now more particularly to Figs. 1 and 2, the high-frequency tubes V_1 and V_2 are each of the double-ended "doorknob" type, which has two terminal pins at opposite ends of the tube for its grid, and also two terminal pins for its plate. Terminal pins (not shown in Fig. 1 or 2) are also provided at opposite ends of each tube for the cathodes thereof. The tube pins 10 and 11, 12 and 13, are connections to the plate electrodes of tubes V_1 and V_2 , respectively, as shown. Pins 12' and 13' are connections to the grid electrode of tube V_2 and the pins 10' and 11', hidden from view in Figs. 1 and 2, are connections to the grid electrode of tube V_1 . Tubes V_1 and V_2 may be mounted upon a chassis or base board 14 by means of bearing block structures 15 as shown. Two backlines or conductive straps 16 and 16' are mounted at their centers upon an

2

insulating support 17, and in the circuit here described function as paralleling inductances. Straps 16 and 16' in the embodiment here illustrated are arcuate in shape, resilient, and so mounted and positioned that normally their ends are strongly urged toward pins 11, 11', 13 and 13' of tubes V_1 and V_2 . Clips 18 and 19 secured to the ends of strap 16 are adapted to engage pins 13 and 11, respectively. A clip 18' is similarly provided at an end of strap 16' for engagement with pin 13' of tube V_2 , and likewise a clip 19' (hidden from view) is provided at the other end of strap 16' for engagement with pin 11'. Blocks 20, preferably of insulating material, are provided to maintain straps 16 and 16' and the clips thereon away from the pins that they normally engage. These blocks each have an open jaw across which extends a removable thumbscrew member 22. Members 22 are adapted to be withdrawn, so that when the clip ends of straps 16 and 16' are disengaged from the tube pins, the straps 16 and 16' may be drawn into the jaws of blocks 20 and the thumbscrew members 22 reinserted in blocks 20 to retain the straps and clips in their disengaged position. In Fig. 1, the broken line position of strap 16 shows it connected to the plate of tube V_2 by engagement of clip 18 with pin 13.

The manner in which the straps 16 and 16' function to increase the operating frequency of the oscillator circuit will become apparent by reference to Fig. 3, wherein is diagrammed a substantially equivalent lumped-constant circuit in a conventional manner. Certain parts in the diagrammatic representation of Fig. 3 are numbered to correspond to like parts in Figs. 1 and 2. Thus straps 16 and 16' are here represented as effective inductances. With these backlines 16 and 16' in parallel, respectively, with the equivalent tuned circuits connected between terminals 10 and 12, and 10' and 12', the effective inductance in each tuned circuit is decreased, resulting in a higher operating frequency.

When the connections at 11, 11', 13 and 13' are broken (paralleling straps 16 and 16' removed), the oscillator covers a lower frequency range.

Although the embodiment described herein employs a resonant line oscillator and double-ended "doorknob" type tubes, the invention may be applied to many other tubes and circuits. Therefore, while there has been described what is at present considered to be a preferred embodiment of this invention, it will be obvious to those skilled in the art that various changes and modifications may be made without depart-

ing from the scope and spirit of the invention as set forth in the appended claims.

What is claimed is:

1. In a high frequency electrical apparatus, the combination including a first and a second vacuum tube, each having at least a plate and a grid, each plate and each grid having at least one terminal pin, two inductances in the form of flexible conductive spring straps each having at its ends means for contacting said pins, insulating means supporting said metal straps at their midpoints, said tubes and straps being so positioned that one said strap may be connected between the plate terminals of said tubes and the other said strap may be connected between the grid terminals of said tubes, and removable retaining means to hold the ends of said straps out of contact with said pins when said straps are disconnected from said pins.

2. In a high frequency electrical apparatus, the combination including a first and a second vacuum tube each having at least a plate and a grid, each plate and each grid having at least one terminal pin, two inductances in the form of conductive spring straps and means at their ends for contacting said pins, said tubes and straps being so positioned that one said strap may be connected between the plate terminals of said tubes and the other said strap may be connected between the grid terminals of said tubes, and retaining means to hold said straps out of contact with said pins when said straps are disconnected from said pins.

3. In a high frequency electrical apparatus including at least one tuned circuit and two terminals connected to opposite ends thereof, an inductance in the form of a conductive spring strap so positioned that its ends may be connected to said two terminals, means supporting said strap at its midpoint, and retaining means to hold the ends of said strap out of contact with said terminals, whereby said strap may be optionally connected between said terminals to increase the resonant frequency of said tuned circuit.

4. In a high frequency electrical apparatus

having at least one tuned circuit and two terminals connected to opposite ends thereof, means for varying the resonant frequency of said tuned circuit, said means including an inductance in the form of a resilient conductive spring strap so mounted and positioned that its ends normally contact said two terminals, and retaining means for optionally holding the ends of said strap out of contact with said terminals.

5. A radio frequency oscillator comprising a first and second vacuum tube, each tube having at least a plate and a grid, each plate and grid having at least two terminal pins, a tuned circuit connected between a terminal pin of each of said plates, a tuned circuit connected between a terminal pin of each of said grids, two inductances in the form of flexible conductive spring straps each being mounted to have its ends normally contacting the other terminal pins of said plates and grids respectively, and retaining means for holding the ends of said straps out of contact with said other terminal pins when said straps are disconnected from said terminal pins.

6. An oscillator in accordance with claim 5 in which each of said straps is fixedly mounted at its center with each of its ends normally in contact with one of said terminal pins and said retaining means include a pair of adjustable screws mounted at fixed points adjacent said terminal pins, said screws in one position holding said straps out-of-contact with said terminal pins and in another position being out-of-contact with said straps whereby said straps contact said terminal pins.
